HUMFREY ANDREWES, OF HIGGATE, LONDON, ENGLAND, ASSIGNOR OF FIFTY PER CENT TO RADIO PATENTS CORPORATION, OF NEW YORK, N. Y., A CORPORATION OF NEW YORK

ELECTRICAL FREQUENCY-CHANGING APPARATUS OF THE THERMIONIC TYPE

Application filed March 5, 1926, Serial No. 92,433, and in Great Britain March 5, 1925

In the use of radio receiving and amplifying apparatus operating upon the well-known method of transforming or changing the frequency of the received signal impulses into another and usually lower radio frequency before amplification and subsequent rectification of the lower radio frequency amplified impulses, certain difficulties are usually experienced. In this method of reception, known also as the "supersonic" amplification method, it is necessary to change the frequency of the incoming signals to a lower frequency suitable for operating the amplifier. This is customarily accomplished by providing a source of radio-frequency oscillations—or "heterodyne"—having a frequency approximating to that of the signals to be received and also some means for combining the said heterodyne oscillations with the incoming signals.

The object of the present invention is to provide an improved apparatus and means for carrying out the frequency changing operation particularly required for receivers of this type, without the disadvantages attendant upon the ordinary arrangement heretofore used.

In many cases using three electrode tubes with this type of receiver wherein the heterodyne or local oscillations are coupled into the circuits carrying the signal currents, some difficulties are often found in arriving at the proper coupling between the two, to ensure proper mixing of the two currents. This difficulty is overcome by the present invention.

Further in one of the arrangements forming the basis of this invention, it is possible to effect a reduction in the number of tubes as compared with the customary methods of frequency changing heretofore employed in conjunction with superheterodyne receivers using three electrode vacuum tubes. The possibilities of radiating radio frequency energy from the receiving aerial are also reduced by the use of this invention as compared with previously known arrangements.

To carry this invention into effect I employ one or more four-electrode thermionic tubes preferably of the type having two grid

or control electrodes, one cathode and one anode.

Where two tubes are used one is employed to provide a local source of heterodyne oscillations, while the other is employed to provide a coupling or combining means between the local heterodyne oscillations and the incoming signals. To this end one of the grid electrodes of the latter tube is connected to the signal receiving and tuning circuit while the second grid electrode is connected to the local source of oscillation provided by the other four-electrode tube.

Two alternative forms of the invention are illustrated in the accompanying drawings, wherein:

Fig. 1 illustrates an arrangement employing two four-electrode tubes of the before-mentioned type, wherein one such tube performs the functions of an oscillator, and the second tube acts as a combining and frequency-changing tube.

Fig. 2 illustrates a simplified arrangement wherein a single tube only is employed which tube performs the dual function of oscillator and frequency changer.

In Fig. 1, V_1 and V_2 represent the two four-electrode tubes just referred to. One of these, namely V_2 is provided with a circuit L_2C_2 in which the local heterodyne oscillations are established by the action of the tube, this circuit is joined between one of the grid electrodes, such as G' and the positive pole of the "B" battery B_2 . This "B" battery is also connected to the anode of the tube. The two grid electrodes are connected together through the condenser C_4 with a grid leak resistance R_2 joined between the grid G'' and the negative pole of the filament lighting battery B_1 .

The tube V_2 provides the local heterodyne oscillations while the tube V_1 provides the coupling means between these oscillations and the signal currents. These signal currents are established in the tuned circuit L_1C_1 by connecting or coupling it to an aerial system in well-known manner as for example through the coupling coil L . Alternatively the point of this circuit which is shown in the diagram as joined to the positive pole of the "B" battery, may be joined to any other

point of zero or substantially zero radio frequency potential, such for example as one or other of the filament terminals of the valve. The tuned circuit L_1C_1 is joined between one of the grid electrodes 2 of the tube V_1 and the positive pole of the "B" battery B_2 . The tube V_1 then operates as a detector tube by virtue of the grid condenser C_5 , and the resistance R_1 so that the amplified signal impulses 5 would normally be repeated in the anode circuit of the said tube this circuit being completed through the "B" battery B_2 . The second grid electrode 3 of this tube is joined in parallel with one of the grid electrodes 2' of 10 the second tube V_2 , so that the potential changes occurring on this grid electrode 2' are thereby communicated to the grid 3 of the first tube V_1 . By this means the plate or anode current flowing through the valve V_1 will 15 be modulated both by the signal impulses communicated to the grid 2' and by the local heterodyne impulses communicated to the grid 3. The results will be the production in the anode circuit of this tube of so called 20 "beat" or "heterodyne" currents having a frequency equal to the difference between the frequencies of the two said sources of modulation. This beat frequency is thereby communicated to the circuit L_3C_3 included in the 25 anode circuit of this tube, and tuned to this beat frequency, from which it is transmitted by the coupling L_3L_4 to the intermediate frequency or long-wave amplifier of any standard and well known type as is commonly done 30 in all previously known receivers of the superersonic type.

The apparatus arranged as shown thus constitutes a complete frequency-changing unit, as its function is to change the frequency of 35 any currents supplied to it through the input coil L , and to deliver lower frequency currents from its output coil L_4 . The said output currents although of lower frequency have impressed upon them any modulation 40 characteristics which may be impressed upon the higher frequency input currents, the fundamental or "carrier" radio frequency only being changed without affecting any lower audio frequency components or modulation 45 of the input currents.

The two tuning condensers C_1 and C_2 may be mechanically coupled together to work in unison from a single control knob or handle, provided that the necessary frequency difference is maintained between the natural frequencies of the two circuits L_1C_1 and L_2C_2 , this difference being equal to or sensibly equal to the frequency of the output currents delivered from the coil L_4 . Provided that 50 the coils L_1 L_2 are similar in electrical constants the desired results can be obtained when the two condensers C_1 and C_2 have electrical characteristics of the "straight-line frequency" type—that is to say such that the electrical capacity of each of these condensers 55

varies in such a manner that equal divisions of movement of the condensers produce equal frequency changes in the two circuits. The two condensers are then directly coupled together with a slight displacement between them to give the necessary frequency difference. This frequency difference will then be maintained at all points on the scale of the condensers provided that they have the above mentioned electrical characteristics.

Alternatively two condensers of normal "straight-line capacity" or "linear type" may be coupled together and two dissimilar coils be used for L_1 and L_2 to give the desired frequency difference. This is indicated in 70 the diagram by dotted lines joining condensers C_1 and C_2 .

Furthermore, in the circuit L_1C_1 and L_2C_2 —the variable condensers may be substituted by fixed condensers, in which case the inductances L_1 , L_2 would be continuously variable and might take the form of variometers. The moveable elements of the two coils or variometers whereby the inductance value is varied may also be mechanically coupled together to work in unison from a single control knob or handle, provided that the necessary frequency difference is maintained between the natural frequencies of the two circuits L_1C_1 and L_2C_2 .

It should be understood that the method of coupling the local heterodyne oscillations to the incoming signal current as herein described is not limited to the use of the precise arrangement of the second tube V_2 set out in 100 the diagram, but may be adapted to any of the previously well known methods of producing heterodyne oscillations. The connections to the two grid electrodes 2' and 3 may likewise be interchanged without departing 105 from the spirit of the invention.

Alternatively, the separate functions of the two four-electrode tubes herein described may be performed in a single tube, as illustrated in Fig. 2. In this arrangement, as in 110 the two-tube method, signals currents are established in the circuit L_1C_1 by coupling to the input circuit L . The tube V_1 then operates as a detector tube by virtue of the grid condenser C_5 and the grid leak R_1 , the circuit L_1C_1 being connected across the grid G''_1 and the filament of the tube V_1 . Local heterodyne oscillations are provided by causing the tube V_1 to oscillate by connecting the inner grid G'_1 to a second circuit L_2C_2 . This circuit is connected between the grid G'_1 and the anode of the tube. Potential changes of the grid G'_1 will therefore cause corresponding changes in the electron stream controlled by the grid G''_1 , on which is impressed the 125 incoming signal and hence the so-called "beat" or "heterodyne" currents will be produced in the anode circuit of the tube. As in the case of the corresponding frequency-changing tube shown in Fig. 1, a third tuned circuit 130

$L_5 C_3$ is also in this instance included in the anode circuit. This anode circuit is tuned to the "intermediate" or supersonic "beat" frequency.

5 Having described my invention, what I believe to be new and desire to secure and protect by Letters Patent of the United States is:—

10 1. In a radio circuit, a four-electrode tube having a heated cathode, an anode and two grid electrodes, one of which is maintained at a positive potential with respect to the other, a grid leak resistance, an oscillatory circuit in which oscillations of the frequency of and due to the received signals are established, one of the grid electrodes being connected therewith, a local source of oscillations of different frequency, said second grid being subject to potential fluctuations therefrom and connected through said "grid leak" resistance to the cathode of the tube, an oscillatory circuit tuned to the resultant or "beat" frequency, and an anode connected to said last mentioned oscillatory circuit.

25 2. Frequency-changing apparatus of the thermionic type, comprising in combination a four-electrode tube having a heated cathode, an anode and a plurality of control electrodes, means including one of said control electrodes for generating oscillations, a second source of oscillations, means including the other control electrode for combining said generated oscillation with said second oscillations to produce a beat note, an output circuit including the anode of the said tube tuned to the beat frequency resulting from the combination of the two frequencies impressed upon the control electrodes and means for maintaining one of said control electrodes positive with respect to the other.

30 3. Frequency-changing apparatus of the thermionic type, comprising a four-electrode tube having a heated cathode, an anode and a plurality of control electrodes, an oscillatory circuit in which signals are received one of the control electrodes of said tube being connected with said oscillatory circuit, a local source of oscillations of different frequency from that of the signal oscillations, a second control electrode subjected to potential fluctuations from said local source of oscillations, means for maintaining said second electrode positive with respect to said first control electrode, and an oscillatory circuit tuned to the resultant or "beat" frequency of said local and received oscillatory currents said anode connected with said last mentioned oscillatory circuit tuned to the resultant or "beat" frequency.

35 4. Frequency-changing apparatus of the thermionic type comprising a four-electrode tube having a heated cathode, an anode and a plurality of grid electrodes, an oscillatory circuit tuned to the incoming signal frequency connected to one of said grids, a local

source of oscillations of different frequency from that of the signal frequency, means for communicating potential fluctuations of the local frequency from the said source to a second grid of the thermionic tube, means for maintaining said second grid at a high positive potential with respect to said first grid and an oscillatory circuit in the anode circuit of the said tube tuned to the resultant or "beat" frequency.

70 5. Frequency-changing apparatus of the thermionic type, comprising a four-electrode tube comprising a first and second grid and a cathode, a source of incoming signals of a predetermined frequency, a circuit tuned to a frequency differing from the frequency of the incoming signals, one of said grid electrodes being connected to the source of incoming signals, the second of said grid electrodes being connected to said last mentioned tuned circuit and means for maintaining said second grid at a positive potential with respect to the first mentioned grid electrode and to the cathode of the tube.

75 6. In a radio circuit, a vacuum tube comprising two grids and a cathode, one of said grids being adjacent said cathode and the second of said grids more remote therefrom, a source of incoming signals of a predetermined frequency, a circuit tuned to a frequency differing from the frequency of said incoming signals, the grid electrode situated nearest to the cathode of the tube being connected to said tuned circuit and means for maintaining said grid electrode at a positive potential with respect to the second grid electrode and to the cathode of the tube, whereby said tube is given a negative characteristic for maintaining oscillations in the said circuit connected with the inner grid electrode.

80 7. In a radio circuit, a four-electrode tube containing a heated cathode, an anode and two grid electrodes, a circuit connected to one grid electrode for receiving the incoming signal, a local source having a frequency differing by a desired amount from that of the incoming signals, a second oscillatory circuit connected to the second grid electrode and to said local source, a third oscillatory circuit connected in series with the anode of the said tube, and tuned to the beat frequency resulting from the intersection of the currents in the first mentioned circuits and means for maintaining the second grid positive with respect to said first grid.

85 8. Frequency-changing apparatus of the thermionic type comprising a four-electrode tube having a heated cathode, an anode and two grid electrodes, an oscillatory circuit, means for generating oscillations of the frequency of and due to the received signals in said oscillatory circuit, one of said grid electrodes being connected to said oscillatory circuit, means including a second four-electrode thermionic tube having a heated cathode and

anode and two grids capacitatively coupled for generating oscillations of different frequency from said first mentioned oscillation, said second grid of said first tube being subject to potential fluctuations of said last mentioned means, and means for maintaining one of said grids of said second tube at a positive potential with respect to the other grid, an oscillatory circuit tuned to the resultant or 10 "beat" frequency and connected to said anode of said second tube, one of said grids of said second tube being connected in said local source of oscillation and also with said second grid of the first mentioned thermionic 15 tube.

9. Frequency-changing apparatus of the thermionic type having in combination a four-electrode tube comprising an anode, a cathode and a first and second grid, said first 20 grid being adjacent said cathode and the second grid more remote therefrom, a circuit tuned to the frequency of received signals and said second grid being connected thereto, a second circuit tuned to a frequency 25 differing from the frequency of the incoming signals, said first grid electrode situated nearest to the cathode of the tube being connected to said second tuned circuit, means for maintaining said first grid at a positive potential 30 with respect to the second grid electrode and to the cathode of the tube whereby said tube is given a negative characteristic for the purpose of maintaining oscillations in the said circuit connected with the inner grid electrode, and an anode circuit connected to said 35 anode tuned to the beat frequency resulting from the combination of the two frequencies impressed upon the grid electrodes.

In testimony whereof I have signed my 40 name to this specification.

HUMFREY ANDREWES.
